UNITED STATES PATENT OFFICE.

JOHN C. IVORY, OF NEWTON, NEW HAMPSHIRE, ASSIGNOR TO DANIEL E. KEMPSTER, TRUSTEE, OF BOSTON, MASSACHUSETTS.

SEAM FOR UNITING MATERIALS.

No. 857,465.

Specification of Letters Patent.

Patented June 18, 1907.

Application filed October 27, 1905. Serial No. 284,659.

To all whom it may concern:

Be it known that I, JOHN C. IVORY, of New-
ton, in the county of Rockingham and State
of New Hampshire, have invented certain
5 new and useful Improvements in Seams for
Uniting Materials, of which the following is
a specification.

This invention relates to improvements in
seams employed to unite the uppers to the
10 soles of turn-shoes or welt-shoes, by the use of
a single thread and fids or toggles acting as
locking members to hold the seam intact.

The invention has for its objects, to form a
very flexible connection or seam between the
15 parts, to reduce the amount, as well as the
cost of the material used in forming the seam,
and to produce a level surface on the sole
when finished.

The invention consists in the use of two
20 threads, one a continuous thread or cord having
bights or loops formed at intervals in its
length which bights or loops are placed or
drawn through a series of perforations in the
parts to be united thereby, one bight or loop
25 for each perforation, combined with another
and preferably cheaper thread cut into sec-
tions, each section forming a fid or toggle in-
serted through each bight or loop of the con-
tinuous thread on the opposite side of the
30 material or the between substance, to that of the
continuous thread, said inserted fids or tog-
gles being independent and detached from
each other between each two bights or loops
35 on the continuous thread, thus forming an
independent locking member for each bight
or loop.

The invention is carried out substantially
as illustrated on the accompanying drawing,
which forms an essential part of this specifi-
40 cation, and whereon like characters of refer-
ence refer to like parts wherever they occur
on the different parts of the drawing.

On the drawing: Figure 1 represents a sec-
tional view of two pieces which are to be
45 united, showing the same connected by my
improved seam when a single cord is used as
the locking member. Fig. 2 represents a
similar view to that shown in Fig. 1, but
showing my improved seam when a loop of
50 thread or cord is used as a locking means.
Fig. 3 represents a detail section of the seam
used as a connection between the upper and
the sole of a turn-shoe. Fig. 4 represents a
similar detail section, showing my improved

seam used to connect the upper and welt to 55
the inner sole of a welt-shoe. Fig. 5 represents
a detail plan view of a portion of the sole of a
boot or shoe in which my improved seam is
used in forming the fair-seam to unite the
outer and the inner soles, or to unite the 60
outer sole to the welt of a welt-boot or shoe.
Fig. 6 represents a sectional side elevation of
that portion of a boot or shoe shown in Fig. 5.

In forming the seams which connect the
upper to the soles of boots or shoes, or the 65
outer soles to the inner soles, or to the welt,
and more especially in connecting the uppers
to the soles of turn-shoes, it is very desirable
that the seam should be made as flexible as is
possible, so as to add to the flexibility of the 70
boot or shoe and to the comfort and ease of
the wearer. It is also desirable that the
amount of the more expensive threads or
cords used in making the seam should be re-
duced as much as possible by the introduc- 75
tion of a less expensive but equally service-
able material in the parts of the seam which
will admit of such an introduction, as a sub-
stantial saving in the amount of the expen-
sive thread may add substantially to the 80
profit in the manufacture of the goods. It is
also desirable that the seam should occupy
as little space as possible within the channel
and thus keep the surface of the sole as level
as possible after the seam has been covered 85
by the finishing lip. It is the object of my
present invention to produce a very flexible
seam, and also to reduce the amount of the
fine quality or expensive thread used, by the
use of locking members which are made from 90
less expensive material and to so arrange the
locking members or fids, as to occupy as little
space as possible within the channel made to
retain such locking members.

The seam consists of a continuous thread 1, 95
which is usually a wax-thread or other strong
and expensive thread. This continuous
thread is formed into a series of bights or
loops 2, which are drawn, inserted, or other-
wise placed within a series of perforations 3, 100
made in the pieces or layers 4 and 5 of the
material to be united by the seam, and so that
the ends of the bights or loops extend through
said perforations and project on the opposite
side thereof to that on which the continuous 105
thread is. The intermediate portions of the
continuous thread, which is between the
bights or loops thereof, rest against the sur-

face of the layer 5 of the material being united by the seam. On the opposite side of the material, resting against the surface of the layer 4 thereof, and inserted within each projecting end of the bights or loops 2, is a short cross or locking member which forms a fid or toggle and which may consist of a single cord or thread 7 of cheaper material than the thread 1, and substantially as shown in Fig. 1; or said locking members may consist of a bight or loop 8 of such cheaper material, and substantially as shown in Fig. 2. I prefer to use a cheap grade of cord or twine in forming these locking members, as the same is sufficiently bulky and flexible to perform the function of such locking members. This series of fids or toggles within the bights or loops 2, prevent such bights or loops from being drawn backward through the perforations in the material, when the thread 1 of the seam is being drawn tight to hold the parts firmly in their proper places.

Each of the locking members is detached and independent of the other locking members, and therefore does not cause any rigidity in the seam, or in the parts which are united by the seam, but leaves the parts as well as the seam perfectly free to move, as the locking members are free to move with the surface of the part of the material against which the locking members rest.

As the tensile strength of the locking members is not necessary to enable them to perform their function, and as their bulk is the only thing necessary, it will be seen that the material from which these locking members are formed may be any kind of cheap cord or twine, such as jute twine, while the thread 1, which retains the layers or parts of the material in their proper united positions by its tensile strength, must be of some stronger and more expensive material, such as a waxed linen or other thread.

My improved seam is designed for use in the manufacture of boots and shoes, and more especially in uniting the soles and uppers. It may be used in forming the seam between the upper 9 and the sole 10 of a turn-shoe, as shown in Fig. 3, or it may be used as the seam between the upper 11, inner sole 12, and the welt 13, of a welt-shoe, as shown in Fig. 4, or it may form the fair-stitch seam 14, which connects the outer sole 15 to the welt 16 and upper 17 of a welt-boot or shoe, as shown in Fig. 6 and in either case the locking member or fid is so arranged as to lie longitudinally within the channel formed on the parts to be united by the seam, and in line with the seam formed in said channel so as to occupy as little space as is possible therein. When the seam forms the fair-stitch seam, the thread may be drawn sufficiently tight to cause the locking members to be drawn into the perforations within which the bights or loops are located, and to such

an extent as to cause them to double upon themselves and to become U-shaped, as shown in Fig. 6. This is more particularly the case when the locking members are made from less bulky and very flexible material, such as a small soft twine or cord. After the seam has been formed, it is covered by a lip as is usual in such cases, and as the fids are arranged so as to occupy as little space as possible within the channel formed to receive the seam, the surface which is exposed after the seam has been covered by the lip will remain substantially level.

I am aware that it is not new to unite material by a seam formed from a continuous thread having loops therein which pass through perforations in the material being united, combined with independent locking members or fids inserted within said loops, and therefore I do not claim such a construction broadly, but I believe that I am the first one to form a seam of this class, in which two threads are used, one being severed so as to form an independent locking member or fid for each loop on a continuous thread, which locking members or fids will be arranged so as to extend longitudinally in line with the series of loops on the continuous thread, whereby a very neat and flexible seam is produced, which will occupy very little space within the channel formed upon the surface of the material for the reception of the seam, and which seam can therefore be covered by the finishing lip of the channel leaving substantially a level surface on the material with the seam completely covered.

Having thus fully described the nature, construction, and the operation of my invention, I wish to secure by Letters Patent and to claim:

A seam consisting of pieces of over-lapped, perforated material, one piece of material having a channel and a lip over hanging the channel, a continuous thread having a series of loops formed throughout its length and passed through alining perforations of the pieces of material, and a locking member disposed between the bight portion of each loop and the outer face of the channeled piece of material with the bight ends of the loops formed for disposition in the channel beneath said lip which overlaps the channel, each locking member being arranged longitudinally in line with the series of perforations of the material and with the portions of the continuous thread intermediate the loops of the latter, the locking members being spaced and independent of one another.

In testimony whereof I have affixed my signature, in presence of two witnesses.

JOHN C. IVORY.
